Primary Examiner — Christy Nemeth(74) *Attorney, Agent, or Firm* — Hawaii Patent Services; Nathaniel K. Fedde; Kenton N. Fedde**CLAIM**

The ornamental design for an electric vehicle charging station, as shown and described.

DESCRIPTION

FIG. 1 is a front, top perspective view of an electric vehicle charging station, showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dashed broken lines in the figures are for the purpose of illustrating portions of the electric vehicle charging station which form no part of the claimed design.

1 Claim, 8 Drawing Sheets(56)
